United States Patent Office.

F. C. PAYNE, OF NEW YORK, N. Y.

Letters Patent No. 77,311, dated April 28, 1868.

IMPROVED FOLDING BED.

The Schedule referred to in these Letters Patent and making part of the same.

TO ALL WHOM IT MAY CONCERN:

Be it known that I, F. C. PAYNE, of the city, county, and State of New York, have invented a new and useful Improvement in Folding Beds; and I do hereby declare that the following is a full, clear, and exact description of the same, reference being had to the accompanying drawings, making a portion of this specification, in which—

Figure 1 is an inverted plan view of a folding bed made according to my invention, showing the same as extended for use.

Figure 2 is a vertical transverse section of the same, representing the bed as folded for transportation or storing.

Figure 3 is a detached view, on an enlarged scale, of one portion of the same.

Similar letters of reference indicate corresponding parts in all the figures.

The object of this invention is to provide a bed, which may be folded into rectangular form without any outwardly-extending or excrescent parts, so that the bed may be conveniently packed either for transportation or to be simply stored away when not in use.

The invention consists in a bed composed of a central and two end-frames bevelled at their adjacent ends, and connected by slotted hinges, in such manner that they, together with the flexible mattress supported thereby, may be readily folded into the form set forth, thus effectually securing the desired result.

To enable others to understand the nature and construction of my invention, I will proceed to describe with reference to the drawings.

A shows a central frame of rectangular form, and provided with the two upwardly-projecting side-pieces *a*, the ends of which are bevelled at an angle of about forty-five degrees, as shown at *a' b'*. The length of this central frame should be about twice the entire thickness of the bed, including not only the frame and springs, but also the mattress forming a portion of the bed.

B represents two end-frames, of suitable length, and of a width corresponding to that of the central frame A, and furnished in like manner with side-pieces, indicated at *b*, the inner ends of these side-pieces, adjacent to the central frame, being bevelled at an angle corresponding to the level of the ends of the side-pieces of the latter, as shown at *c' d'*.

Each of the end-frames B has attached to the inner end of its side-pieces, *b*, a plate or lug, *c*, in which is formed a curved slot, *c**. The extremities of these lugs extend past the adjacent ends of the side-pieces, *a*, of the central frame, and are attached thereto by broad-headed screws or pins, *d*, which are preferably fixed to plates *b**, secured in their turn by any suitable means to the central frame, as shown in fig. 2.

Each of the frames A and B is designed to be constructed with transverse bottom slats, *e*, upon which are arranged suitable springs, *g*, which support a flexible mattress, C, placed thereon, with its ends attached to the end-pieces *g** of the end-frames.

In order to fit the bed for use, it is only necessary to bring the frames A B in line with each other, and in a horizontal position, the slots *c** in the lugs *c* of the hinges permitting such movement of the frames as to enable their adjacent ends to come together, as shown in fig. 1.

When it is desired to fold the bed, as for packing away when not in use, or for transportation, the two end-frames are turned into a position parallel with each other, and at right angles to that of the central frame, the bevelled form of the ends of the side-pieces of the several frames and the slots *c** in the hinges enabling the central frame to fit nearly or quite across the end of the package formed by the folded bed, as shown in fig. 2, thus securing the rectangular form desired, while the length of the central frame A, being twice the entire thickness of the bed, as hereinbefore mentioned, the entire space between the two end-frames, when thus parallel with each other, is filled by the springs, mattress, &c., and the bed is thus folded into compact as well as symmetrical and convenient shape, with no portion thereof extending outward in an unsightly manner, or forming, as it were, an excrescence thereon.

What I claim as my invention, and desire to secure by Letters Patent, is—

The bed, composed of the central frame A and two end-frames B, bevelled at their contiguous ends, and connected by the slotted hinges *c d*, in such manner that, with the mattress attached thereto, they may be brought or folded into rectangular form without outwardly-extending or excrescent parts, substantially as herein set forth.

F. C. PAYNE.
